FIRE EXTINGUISHING INSTALLATION

Howard Edwin Bedford, Brentford, England, assignor, by mesne assignments, to Pyrene Manufacturing Company, Newark, N. J., a corporation of Delaware

Application August 27, 1946, Serial No. 693,336
In Great Britain September 3, 1945

9 Claims. (Cl. 169—4)

1

This invention relates to an improved construction and arrangement for delivering fire extinguishing foam to a tank for the purpose of spreading a blanket of the foam over the surface of the material contained in the tank.

Oil tanks and other containers of highly inflammable material have heretofore been provided with fixed installations for the delivery of fire extinguishing foam upon the outbreak of a fire. These arrangements have been such that the foam delivered to the tank will be spread as a blanket over the surface of the inflammable material to thus exclude the access of air to the material. Installations of this character have usually included a riser or supply pipe extending upwardly along the outside of the tank and connected at its upper end to a spreading or other delivery device extending into the tank. It has been recognized as desirable to test fire extinguishing equipment of this character periodically in order to make certain that it will be in good operating condition when it is required in an emergency. In prior arrangements the testing of the fire extinguishing equipment has almost invariably resulted in the introduction of a quantity of foam into the tank so that the contents is diluted or contaminated to a certain extent.

Frequently it has been found desirable to provide a vapor seal in connection with the device through which the fire extinguishing foam is introduced in order to prevent the escape of vapors or gases from the top of the tank through the foam delivery pipe. In prior arrangements considerable difficulty has usually been encountered in the replacement of the vapor seals which ordinarily are formed of relatively thin, flexible material, such as cellophane, capable of preventing the escape of the vapors but being at the same time readily broken by the stream of foam delivered under pressure. These vapor seals are usually broken in the course of the periodic tests and their replacement entails a considerable amount of work.

It has been a primary object of the present invention to provide an arrangement in which the foam generating and delivering equipment may be readily tested periodically without the introduction of foam into the tank.

Another object has been to provide equipment of the character indicated which is very simple in construction and which may be expeditiously prepared for testing and then restored to its operative condition after the test has been performed.

2

A further object of the invention has been to provide an installation for delivering foam to a sealed tank which permits the testing of the foam producing and delivering equipment without breaking the vapor seal. In connection with this phase of the invention it has also been an object to provide simple means, adapted for quick operation, for inspection, introduction or replacement of the vapor sealing means.

Still another object of the invention has been to provide an arrangement of the character indicated which is sturdy and durable and less subject to damage in the course of use and repair than prior installations. Related to this is the further object of so constructing and arranging the foam delivery means that they are accessible for inspection and repair directly from the roof of the tank, thus eliminating the need for extra ladders. It is a feature of the invention in this connection, to provide the high point of the foam delivery system as close as possible to the wall of the tank and just below the level of the roof. As a result, if the roof of the tank becomes displaced and is caused to fall or rest upon the high point of the foam delivery system the leverage through which the force will act upon the connection with the tank wall will be relatively short.

Other objects, features and advantages of the invention will appear from a detailed description of an illustrative embodiment of the same and certain modifications which will now be given in conjunction with the accompanying drawings:

Figure 1 is a view, partially in elevation and partially in vertical section, showing a portion of the top of a large tank and a portion of the riser with the improved connection therebetween.

Figure 2 is a similar view of the same parts taken at right angles to Figure 1.

Figures 3 and 4 are views similar to Figures 1 and 2, but with the swivelled hood turned about its axis through 90°.

Figure 5 is a view similar to Figure 1 showing a modified form of connection between the riser and the foam intake member, and

Figures 6 and 7 are similar views showing two further modifications of the connection between the riser and foam intake.

In connection with the present invention a foam intake fitting is mounted on and passes through the side wall of the tank at a point adjacent the top. This fitting is preferably elbow shaped and provided with an upwardly facing, horizontally disposed intake port. The intake port is located adjacent to the upper end of a

vertically extending riser through which the fire extinguishing foam is delivered from the foam producer at a distant point. A shiftable hood member serves to connect the upper end of the riser with the intake port of the fitting carried by the tank. In normal operation the foam is directed upwardly through the riser against the underside of the hood and is then deflected downwardly into the intake port and into the tank for distribution over the surface of the oil. The hood, however, is capable of being shifted in whole or in part so as to expose the intake port for the replacement of the vapor seal, if one is provided, and to divert the foam away from the intake port. Various arrangements of the connecting hood may be provided for accomplishing the foregoing purposes.

Referring now to the drawings, there is shown in Figure 1 a portion of the top of a tank 10 adapted to retain oil or other inflammable material. A roof 11 is provided at the top of the tank. Through the side wall an inlet opening 12, for fire extinguishing foam, is provided, as best shown in Figure 2, and this opening is preferably reinforced by a plate 13 which is riveted or bolted or otherwise secured to the wall of the tank and provided with a central opening aligned with the opening 12. Integral with, or otherwise connected with, the plate 13 is a small hood 14 extending inwardly into the tank and arranged to direct the foam downwardly within the tank. An extension 15 of the curved top of the hood serves to deflect the foam toward the wall of the tank and assists in spreading the foam over the surface of the inflammable material in the tank.

A foam inlet fitting 16 has a main conduit portion 17, preferably of elbow configuration and rectangular in cross section, and has at its inner end a flange 18 adapted to be riveted, bolted or otherwise secured to the plate 13. The conduit 17 of the fitting 16 extends outwardly away from the tank and then upwardly to provide a horizontally disposed intake port which is surrounded by a flange 19 integral with or otherwise secured to the upper end of the conduit.

A foam delivery riser 20 extends upwardly along the side wall of the tank and is provided at its upper end with a horizontally disposed flange 21. It will be understood that any suitable form of foam producing equipment may be provided for delivering fire extinguishing foam to and through the riser 20. For example, means of the type disclosed in my Patent No. 2,373,009, granted April 3, 1945, may be provided for the production of air foam for delivery to and through the riser 20. A pipe section or sleeve 22, having at its lower end a radially extending flange 23 adapted to be bolted or otherwise secured to the flange 21, provides an upward extension of the riser. At its upper end the section 22 is provided with a laterally extending flange 24. This is at a slight distance below the free upper end of the sleeve. A hood 25, having in its bottom adjacent one end a circular opening adapted to fit over and snugly receive the upper end of the sleeve 22, is provided with a laterally extending flange 26, which may be bolted or otherwise detachably secured to the flange 24. Hood 25, as best shown in Figure 2, extends laterally at the top of the sleeve 22 and is provided with a downwardly sloping top 27 which merges into the flange 26. The sloping top 27 is normally positioned directly over the intake port of the fitting 16. Flange 26 may, if desired, be bolted or otherwise secured to the flange 19 to insure a firm and tight connection between these

parts. The underside of the hood 25 is provided with an opening corresponding with the intake port of the fitting 16 and normally aligned with the latter when the hood is in the position shown in Figures 1 and 2.

If desired, a vapor seal formed of cellophane or other flexible, impervious material, capable of preventing the discharge of vapors from the tank and adapted to be readily broken by the pressure of the foam in the event of a fire, may be provided within the intake port of the fitting 16. For this purpose a frame 28 may be welded or otherwise secured to the fitting 16 at a slight distance inwardly from the face of the flange 19. A vapor sealing member 29 may be extended across this frame in any suitable way. It may be clamped in place between the parts of a removable frame 30 adapted to be secured to the frame 28 by screws 31 or the like. The arrangement is preferably such that the upper ends of the screws 31 are flush with or slightly below the level of the outer face of the flange 19.

Whenever it is desired to replace the vapor sealing member 29 or to test the foam producing equipment, the bolts or other securing means connecting the hood 25 with the flanges 19 and 24 are removed and the hood may then be rotated, by means of a hand wheel 32 attached to the hood, about the axis of the riser to carry the discharge spout of the hood away from the fitting 16 into the position indicated in Figures 3 and 4. As best shown in Figure 3, any foam delivered upwardly into the riser will at this time be discharged, as indicated at 33 away from the tank and away from the fitting 16. At the same time the intake port of the fitting 16 will be exposed for inspection or replacement of the vapor seal.

In lieu of swiveling the hood 25 about the upper end of the sleeve 22, the hood may, if desired, be mounted for sliding movement as shown in Figure 5. A track or guideway 34 may be provided in association with the flanges 19 and 24 and the hood 25a may be shifted either to one side or the other along this track or guideway upon the loosening of the securing bolts. If the hood is shifted toward the left in Figure 5 it will expose the intake opening of the fitting 16 with its vapor seal member, if one is provided. Moreover, when in this position, any foam which may be delivered for test purposes into the riser will be discharged downwardly at the opposite side of the riser and will not enter the tank. If desired, provision may be made for the sliding of the hood only in this one direction. However, if it is made slidable also in the opposite direction the upper end of the riser and the extension sleeve 22 will be exposed for inspection and cleaning. In that event, also, the foam for testing purposes may be discharged upwardly while the intake opening and vapor seal of the fitting 16 will be protected by the hood.

In Figure 6 there is shown another modification in which the hood 25b is hingedly mounted upon the flange 24 of the riser extension 22 by means of a hinge 35. With this type of construction the bolts or other securing means for retaining the hood in normal operative position may be removed and the hood swung about the hinge into the position indicated in broken lines. At this time the intake opening and vapor seal member will be exposed, as will also the upper end of the riser extension 22. Any foam delivered into the latter for test purposes will then simply be discharged vertically into the atmosphere. If desired the

hinge could be provided along one of the longer sides of the hood and function in the same manner.

A further modified construction is shown in Figure 7. Here the hood is formed in two sections 36 and 37, which are hinged together at 38. Normally the two sections of the hood will be secured respectively to the flanges 19 and 24 by bolts, screws or the like. However, if it is desired to test the foam producing equipment the section 36 may be released and thrown upwardly about the hinge 38 to expose the upper end of the extension 22 and permit the discharge of the foam upwardly into the atmosphere. If it is desired to inspect or replace the vapor seal in the intake port of the fitting 16, the section 37 of the hood is released and swung upwardly about the hinge 38. If desired, each section could be hingedly secured along a lower edge to the associated supporting flange and the two sections then merely locked together in some suitable way, as by bolts or the like.

In all of the arrangements described above the hood-like member and associated parts are preferably disposed close to and just below the roof of the tank so that all work on the parts may be carried out from the roof without the use of ladders, cradles or special tools.

While several illustrative embodiments of the invention have been described in considerable detail, it will be understood that numerous changes may be made in the construction and arrangement of the various parts without departing from the scope and principles of the invention.

I claim:

1. In apparatus of the class described a tank, means for delivering fire extinguishing foam to said tank, including a riser extending vertically along the side of said tank, said riser having a horizontally disposed laterally extending flange at its upper end, a hood mounted on said flange and having a discharge opening spaced horizontally from the axis of said riser, and an inlet fitting secured to said tank adjacent said riser, said fitting having an inlet adapted to register with said discharge opening when said hood is in one position and being adapted to deliver foam discharged thereby into the interior of said tank, said hood and riser having interfitting portions arranged to permit turning of said hood about the axis of said riser.

2. In apparatus of the class described a tank, means including a riser extending vertically along the side of said tank for delivering fire extinguishing foam thereto, an inlet fitting secured to said tank adjacent the upper end of said riser but spaced horizontally therefrom, hood means carried at least in part by said riser adapted to connect the upper end of said riser with said inlet fitting for delivering foam to said tank, and means for mounting at least a part of said hood means for movement relative to said riser to a position in which it enables the discharge of said foam in a direction away from said inlet fitting, said mounting means serving to support at least said part of said hood means in its movement into said position and to confine such movement to a predetermined path.

3. In apparatus of the class described a tank, means including a riser extending vertically along the side of said tank for delivering fire extinguishing foam thereto, an inlet fitting secured to said tank adjacent the upper end of said riser, said fitting having an inlet opening spaced hori-

zontally from said riser, means on said fitting for retaining a vapor seal across said opening, movable hood means carried at least in part by said riser adapted to connect the upper end of said riser with said inlet fitting for delivering foam to said tank, and means for mounting at least a part of said hood means for movement relative to said riser to a position in which said foam is caused to be directed away from said inlet fitting, said mounting means serving to support at least said part of said hood means in its movement into said position and to confine such movement to a predetermined path.

4. In apparatus of the class described a tank, means including a riser extending vertically along the side of said tank for delivering fire extinguishing foam thereto, an elbow shaped inlet fitting secured to said tank adjacent the upper end of said riser, said fitting having an inlet passage therethrough provided with a horizontally disposed intake port, means for retaining a vapor seal member across said intake port, movable hood means normally disposed substantially horizontally to connect the upper end of said riser with said inlet fitting for delivering foam to said tank, said hood means having a horizontally disposed discharge port adapted to register with said intake port but movable out of registry therewith to direct foam delivered through said riser away from said intake port, and means connected with said riser for supporting said hood means during its movements into and out of registry with said intake port and for confining said movements to a predetermined path.

5. In apparatus of the class described a tank, means including a riser extending vertically along the side of said tank for delivering fire extinguishing foam thereto, an inlet fitting secured to said tank adjacent the upper end of said riser, said fitting having an inlet passage therethrough provided with a horizontally disposed intake port, slideable hood means adapted to connect the upper end of said riser with said inlet fitting for delivering foam to said tank, said hood means being slideable to a position to cause discharge of said foam away from said inlet fitting, and means connected with said riser for supporting said hood means and for confining the same to a predetermined path in its sliding movements.

6. In apparatus of the class described a tank, means including a riser extending vertically along the side of said tank for delivering fire extinguishing foam thereto, an inlet fitting secured to said tank adjacent the upper end of said riser, said fitting having an inlet passage therethrough provided with a horizontally disposed intake port, and pivotally mounted hood means adapted to connect the upper end of said riser with said inlet fitting for delivering foam to said tank, said hood means being swingable about its pivot to a position to cause discharge of said foam away from said inlet fitting, the pivot of said hood means serving to confine said hood means to a predetermined path in its movement to said position and to support the same in said position.

7. In apparatus of the class described a tank, means including a riser extending vertically along the side of said tank for delivering fire extinguishing foam thereto, an inlet fitting secured to said tank adjacent the upper end of said riser, said fitting having an inlet passage therethrough provided with a horizontally disposed intake port, hood means carried at least in part by said riser and adapted to connect the upper end of said riser with said inlet fitting, and hinge means

connected with at least a part of said hood means arranged to permit swinging of said part to expose the upper end of said riser and cause the delivery of foam into the atmosphere, said hinge means serving to confine said part of said hood means to a predetermined path in its swinging movement and to support the same when it is swung to expose the upper end of said riser.

8. In apparatus of the class described a tank, means including a riser extending vertically along the side of said tank for delivering fire extinguishing foam thereto, an inlet fitting secured to said tank adjacent the upper end of said riser, said fitting having a horizontally disposed intake port, means for retaining a sealing member on said inlet fitting, a plurality of connected hood sections adapted to provide a passage connecting the upper end of said riser with said inlet fitting, a hinge serving to connect said hood sections, one of said hood sections being tiltable to expose said sealing member.

9. In apparatus of the class described a tank, means including a riser extending vertically along the side of said tank for delivering fire extinguishing foam thereto, an inlet fitting secured to said tank adjacent the upper end of said riser,

5
10
15
